UNITED STATES PATENT OFFICE

LILLIAN L. HURST, OF SAN JOSE, CALIFORNIA

HAIRDRESSING ARTICLE

Application filed October 25, 1929. Serial No. 402,487.

My invention relates to improvements in a hair dressing article, and the primary object thereof is the provision of means for waving, curling, pressing and dressing hair that is efficient, simple of structure, inexpensive to manufacture and readily applied, for the purposes mentioned, by the novice as well as by the professional.

With the foregoing and further objects and purposes in view which will appear as the description proceeds, my invention resides in the construction, arrangement and employment of parts hereinafter described and claimed, it being understood that changes in the precise embodiment of the invention herein disclosed can be made within the scope of what is claimed without departing from the spirit of the invention.

In the accompanying drawings—

Figure 1 is a bottom perspective view of the present hair dressing article;

Figure 2 is a perspective view of its upper side;

Figure 3 is a bottom plan view of the device, closed;

Figure 4 is an edge view thereof, partly closed;

Figure 5 is a view approximately on line 5'-5' of Fig. 1;

Figure 6 is a median longitudinal sectional view;

Figure 7 is a top plan view of a portion of the frame or rigid element of the device;

Figure 8 is a plan view of a portion of the tongue or resilient element; and

Figure 9 is a sectional view approximately on line 9'-9' of Fig. 7.

Referring to the drawings in detail, throughout which like reference characters designate like parts:

The numerals 1 and 2 designate the frame element and tongue element, respectively, of the present hair dressing article.

The frame element 1, which is preferably substantially non-flexible and for which purpose it is provided with upwardly projecting flanges 3 extending along its side edges, is bowed longitudinally and has its forward end portion narrowed transversely, the extremity thereof being doubled back to form

a comparatively flat loop 4, the function of which will become apparent as the description continues, and has its opposite end portion provided with a transversely extending slot 5 and portions of the element intermediate said slot and the terminus of said end portion doubled together (see Figs. 7 and 9) to form a bearing 6, more or less cylindrical in cross section, for rotatably supporting the looped end 7 of the tongue element 2.

The element 2, which is preferably formed of sheet spring steel to impart thereto the proper resiliency, is also bowed or arcuated longitudinally, but which arcuation is considerably more acute than the arcuation or bowing of its cooperable frame element 1, whereby when its looped end 7 is pivotally mounted on the bearing 6 and it is caused to bear against the lower side of the frame element 1 at 8 its free end 9 will be in spaced relation to the loop 4 (see Fig. 4).

The elements 1 and 2 are considered to be in "closed" position when the degree of arcuation of the tongue 2 is reduced to correspond substantially to the radius or arcuation of the lower side of the frame element by spring pressing it thereagainst until its free end 9 may be entered in the loop 4 (see Fig. 6).

The loop 5 is intended to have sufficient "play" on the bearing 6 to permit the free end 9 of the tongue element 2 to be moved transversely in either direction relative to the frame element 1 (see broken lines Fig. 3) in order to permit it being entered in, or removed from, the loop 4.

In applying my improved hair dressing article for the purposes set forth, the tongue element 2 is slipped along the scalp of the subject underneath a selected division of the hair. The frame element 1 is then pressed down on said hair to pinch it tightly between said elements, the free end of the tongue element is then caused to enter and engage the loop 4 for temporarily locking said elements together with the hair bound firmly therebetween. The hair on either side of the device may then be combed out, waved, puffed, or treated or dressed in any manner desired. Any number of the articles, found desirable, may be employed for dressing the hair of a

subject. The devices may be removed at any time desired after dressing the hair, by disengaging the free end of the tongue element from the loop 4 and drawing the tongue from 5 underneath the hair.

What I claim and desire to secure by Letters Patent, is:

1. A hair dressing article of the character described, comprising, a frame element, and 10 a tongue element pivotally supported thereby, said frame element having upwardly projecting flanges extending longitudinally along the side edges thereof. 75
15. 2. A hair dressing article of the character described, comprising, a frame element bowed upwardly longitudinally intermediate its ends and having upwardly projecting flanges on its side edges, and a cooperable flexible tongue element having one end pivoted on 20 said frame element, said tongue element bowed longitudinally. 80
25. 3. In a hair dressing article of the character described, a comparatively broad frame element arcuated longitudinally and having spaced flanges extending longitudinally thereof, and a relatively narrow resilient tongue element having one end pivoted to one 30 end of said frame element, the free end of said tongue element being movable relative to said frame element for engaging it with a loop on one end of said frame element for removably locking registering ends of said elements together. 85
35. 4. In a hair dressing article of the character described, a frame element formed of an oblong strip of flat metal and having an upwardly projecting flange extending longitudinally thereof, said element being arcuated longitudinally, and a tongue element formed 40 of a relatively narrower oblong strip of resilient metal having one end formed into a loop for pivotally connecting it to one end of said frame element and whereby said tongue element may be rotated into bearing 45 engagement with the lower side of said frame element. 90
50. 5. In a hair dressing article of the character described, a substantially rigid frame element embodying an oblong strip of flat metal arcuated longitudinally and having an upwardly projecting flange extending longitudinally thereof, a relatively narrower resilient tongue element formed of an oblong strip of flat metal, said tongue element arcuated longitudinally and having a loop at 55 one end pivotally mounted to rotate on a bearing on one end of said frame element, whereby said tongue element may be moved into operable position along the lower side of the frame element for binding hair therebetween, and means on the free end of one of said elements engageable with the free end of the other element for removably locking said 60 free ends together. 95
65. 6. In a hair dressing article of the character described, a substantially rigid frame element embodying an oblong strip of flat metal arcuated longitudinally and having an upwardly projecting flange extending longitudinally thereof, a relatively narrower resilient tongue element formed of an oblong strip of flat metal, said tongue element arcuated longitudinally and having a loop at one end pivotally mounted to rotate on a bearing on one end of said frame element, whereby said tongue element may be moved into operable position along the lower side of the frame element for binding hair therebetween, and means on the free end of one of said elements engageable with the free end of the other element for removably locking said 70 free ends together. 100
75. 7. In a hair dressing article of the character described, a substantially rigid frame element embodying an oblong strip of flat metal arcuated longitudinally and having an upwardly projecting flange extending longitudinally thereof, a relatively narrower resilient tongue element formed of an oblong strip of flat metal, said tongue element arcuated longitudinally and having a loop at one end pivotally mounted to rotate on a bearing on one end of said frame element, whereby said tongue element may be moved into operable position along the lower side of the frame element for binding hair therebetween, and means on the free end of one of said elements engageable with the free end of the other element for removably locking said 80 free ends together. 105
85. 8. In a hair dressing article of the character described, a substantially rigid frame element embodying an oblong strip of flat metal arcuated longitudinally and having an upwardly projecting flange extending longitudinally thereof, a relatively narrower resilient tongue element formed of an oblong strip of flat metal, said tongue element arcuated longitudinally and having a loop at one end pivotally mounted to rotate on a bearing on one end of said frame element, whereby said tongue element may be moved into operable position along the lower side of the frame element for binding hair therebetween, and means on the free end of one of said elements engageable with the free end of the other element for removably locking said 85 free ends together. 110
90. 9. In a hair dressing article of the character described, a substantially rigid frame element embodying an oblong strip of flat metal arcuated longitudinally and having an upwardly projecting flange extending longitudinally thereof, a relatively narrower resilient tongue element formed of an oblong strip of flat metal, said tongue element arcuated longitudinally and having a loop at one end pivotally mounted to rotate on a bearing on one end of said frame element, whereby said tongue element may be moved into operable position along the lower side of the frame element for binding hair therebetween, and means on the free end of one of said elements engageable with the free end of the other element for removably locking said 95 free ends together. 115
100. 10. In a hair dressing article of the character described, a substantially rigid frame element embodying an oblong strip of flat metal arcuated longitudinally and having an upwardly projecting flange extending longitudinally thereof, a relatively narrower resilient tongue element formed of an oblong strip of flat metal, said tongue element arcuated longitudinally and having a loop at one end pivotally mounted to rotate on a bearing on one end of said frame element, whereby said tongue element may be moved into operable position along the lower side of the frame element for binding hair therebetween, and means on the free end of one of said elements engageable with the free end of the other element for removably locking said 105 free ends together. 120
110. 11. In a hair dressing article of the character described, a substantially rigid frame element embodying an oblong strip of flat metal arcuated longitudinally and having an upwardly projecting flange extending longitudinally thereof, a relatively narrower resilient tongue element formed of an oblong strip of flat metal, said tongue element arcuated longitudinally and having a loop at one end pivotally mounted to rotate on a bearing on one end of said frame element, whereby said tongue element may be moved into operable position along the lower side of the frame element for binding hair therebetween, and means on the free end of one of said elements engageable with the free end of the other element for removably locking said 115 free ends together. 125
120. 12. In a hair dressing article of the character described, a substantially rigid frame element embodying an oblong strip of flat metal arcuated longitudinally and having an upwardly projecting flange extending longitudinally thereof, a relatively narrower resilient tongue element formed of an oblong strip of flat metal, said tongue element arcuated longitudinally and having a loop at one end pivotally mounted to rotate on a bearing on one end of said frame element, whereby said tongue element may be moved into operable position along the lower side of the frame element for binding hair therebetween, and means on the free end of one of said elements engageable with the free end of the other element for removably locking said 125 free ends together. 130

In testimony of the foregoing being my own, I have hereunto affixed my signature this 14th day of October, 1929.
